UNITED STATES PATENT OFFICE.

FREDERICK W. COLE, OF CHICAGO, ILLINOIS.

EGG-CASE FLAT.

Application filed September 23, 1926. Serial No. 137,208.

This invention relates to egg case flats for use in various types of crates commonly employed for shipping eggs.

One of the most common types of flat now in use comprises a backed corrugated flat having grooves or cut-away portions transversely of the corrugations to receive the lower edges of the filler. Such a flat, while possessing many advantages, is relatively expensive to make since it requires pasting the back to the corrugated portion and forming the transverse grooves.

The present invention has for one of its objects to provide an egg case flat formed of a single integral sheet of relatively heavy fiber board stamped to form grooves for the filler and provided with projections in the intermediate raised portions to contact and cushion the eggs.

20 A further important object of this invention is to provide a simple, inexpensive egg flat adapted to cushion the eggs effectively against breaking during shipment.

A further important object of this invention is to provide an egg case flat having regularly stamped grooves for receiving the lower edge of the filler and intermediate raised portions provided with oppositely extending projections adapted to contact the eggs and cushion the same against breaking.

Other and further important objects of this invention will be apparent from the disclosures in the specification and the accompanying drawings.

35 This invention (in a preferred form) is illustrated in the drawings and hereinafter more fully described.

On the drawings:

Figure 1 is a top plan view of a blank for egg case flats embodying the principles of this invention.

40 Figure 2 is an enlarged fragmentary view of the same.

Figure 3 is a sectional view taken on line III-III of Figure 2.

45 Figure 4 is a fragmentary view illustrating one type of finished egg flat.

Figure 5 is a sectional view taken on line V-V of Figure 4.

50 Figure 6 is a fragmentary view of a modified form of my invention.

Figure 7 is a sectional view taken on line VII-VII of Figure 6.

55 Figure 8 is a fragmentary plan view of a second modified form of my invention.

Figure 9 is a sectional view taken on line IX-IX of Figure 8.

As shown on the drawings:

In the manufacture of egg flat embodying the principles of this invention, relatively heavy fiber board having a calibre of substantially .030 of an inch thickness is preferably used. A sheet of such fiber board of the dimensions commonly employed in egg case flats possesses sufficient strength without requiring any additional reinforcing or backing means to support the eggs without buckling. In Figure 1 there is shown a blank for egg case flats indicated by the reference numeral 1 preferably stamped from a sheet of fiber board of the above characteristics. Any suitable stamping operation may be employed to provide substantially rectangular raised portions 2 spaced apart to form transversely extending intersecting grooves 3 for receiving the lower edges of the filler. In the stamping operation the fibers in the upwardly crowded portions 4 are stretched to a certain extent and rendered more or less resilient.

The blank above described is next subjected to other stamping operations to form the finished flats illustrated in the remaining figures. In Figures 4 and 5, illustrating one type of egg flat, a plurality of projections 5 are formed by punching the sheet with sufficient force to rupture the sheet, thereby forming openings 6 and upstanding points 7. Said projections 5 are preferably formed at regularly spaced distances from the corners of the raised portions 2 and are primarily adapted to contact the surface of the larger ends of the eggs. In the same or subsequent stamping operation the central portion of the raised portion 2 is depressed to form a circular depression 8, the bottom of which is punched out to form an opening 9 surrounded by downwardly projecting points 10. It will be apparent that if the base of the egg rests in the circular depression 8 with its sides contacted by one or more of the points 7, that the points 10 will afford a cushioning effect between the base of said egg and the end of the egg in the tier next below. Of course ideal conditions could be such that the small end of the egg in the tier below would be held in upright position by the prongs or points 10 but such ideal conditions would never be completely realized since the size and position of the eggs are never uniform. In any event, however, the upwardly projecting prongs 7

and the downwardly projecting prongs 10 serve to provide an effective cushioning between the adjacent upper and lower tiers of eggs.

5 In Figures 6 and 7 there is shown a second modified form of egg case flat in which alternate projections 11 and 12 extend in opposite directions. Said projections 11 and 12 are formed as before by punching the sheet 10 sufficiently to rupture the same, with the punches preferably arranged in a circle substantially the diameter of the larger portion of the egg. Said projections 11 and 12 thereby serve to prevent the eggs from either side 15 of the flat from coming in contact with opposite sides of the same area of the raised portion 2.

In Figures 8 and 9, instead of the punched projections as shown in the previous figures, 20 the raised portions 2 are provided with annular concentric corrugations 13 and 14. As viewed from the top of the flat, the annular corrugation 13 represents a depression and the annular corrugation 14 a projection extending substantially one-half between the plane of the bottom of the corrugation 13 and the surface of the raised portion 2. A further central depression 15 is formed within the annular corrugation 14. An efficient 25 cushioning effect is thereby provided between the eggs in adjacent tiers, since no matter what the angle of the eggs, there is almost certain to be an air space between the adjacent 30

portions of the eggs contacting the two sides of the flat. It should be further pointed out 35 that during the stamping process the fibers of the flat are alternately stretched and compressed in such a way as to render the structure relatively resilient without substantially weakening the supporting strength of the flat. 40

It should be understood that the specific arrangement of the projections and corrugations in each of the raised portions 2 of the egg case flat may be varied within certain limits, provided that the cushioning effect produced by the oppositely extending projections or corrugations is not thereby lessened. 45

I am aware that many changes may be made, and numerous details of construction may be varied through a wide range without 50 departing from the principles of this invention, and I therefore do not purpose limiting the patent granted hereon, otherwise than necessitated by the prior art.

I claim as my invention:

An egg case flat, having intersecting grooves formed therein for receiving a filler and raised portions defined by said grooves, oppositely extending punched projections being formed in said raised portions for contacting the eggs, said projections alternately extending in opposite directions. 55 60

In testimony whereof I have hereunto subscribed my name.

FREDERICK W. COLE.
